UNITED STATES PATENT OFFICE.

CHARLES MONDENG, OF MINNEAPOLIS, MINNESOTA.

HONEY-BOX MACHINE.

SPECIFICATION forming part of Letters Patent No. 655,938, dated August 14, 1900.

Application filed September 1, 1899. Serial No. 729,157. (No model.)

To all whom it may concern:

Be it known that I, CHARLES MONDENG, a citizen of the United States, residing at Minneapolis, in the county of Hennepin and State 5 of Minnesota, have invented certain new and useful Improvements in Honey-Box Machines; and I do hereby declare the following to be a full, clear, and exact description of the invention, such as will enable others skilled 10 in the art to which it appertains to make and use the same.

My present invention relates to a machine for making honey-boxes or so-called "honey-box sections," and is in the nature of an improvement 15 on the machine disclosed and claimed in my Patent No. 629,167, issued of date July 18, 1899, entitled "Honey-box machine."

The primary object sought to be attained 20 by my present invention by way of improvement over my prior machine is increased speed or efficiency. My said prior machine, while efficient and as rapid as any prior machine of the same character, was not capable 25 of the maximum possible speed of an ideal machine for the above purpose.

By my present invention I believe I have accomplished practically a maximum or highest possible speed of which a machine of this 30 character is capable, this result being attained by so timing and exposing the various cutters and other parts that no time is lost during the short intervals required by the operator to collect and present the blank strips to the 35 machine.

The above features and others will clearly appear from a consideration of the machine herein illustrated and presently to be described.

40 The invention is illustrated in the accompanying drawings, wherein like characters indicate like parts throughout the several views.

Figure 1 is a plan view of the machine constructed in accordance with my invention. Fig. 2 is a left side elevation of the machine. Fig. 3 is a rear end elevation of the machine, some parts being broken away and others removed. Fig. 4 is a horizontal section taken 45 approximately on the line $x^4 x^4$ of Fig. 5. Fig. 5 is a longitudinal vertical section taken approximately on the line $x^5 x^5$ of Fig. 1; and

Fig. 6 is a view corresponding in the line of its section to Fig. 5, but showing only the rear end portions of the said parts shown in Fig. 5, and certain of the parts being shown in different positions.

A horizontal bed-plate a is supported by side brackets a' . On the face of this bed-plate a rectangular channel z , through which the blanks are fed laterally, is formed by the co-operation with the said bed-plate of longitudinally-extended end guides $a^2 a^3$ and overhead guides a^4 . The end guides a^2 are parallel, and in line with the inner surface of each 60 is a small circle-saw b , both of which saws are carried by a transverse shaft b' , suitably mounted in bearings b^2 on the side brackets a' and provided with a pulley b^3 , over which a belt (not shown) is run to impart motions 65 to said saws. There is but one of the guide-surfaces a^3 , and this extends outward from the adjacent saw b . At the opposite side of the machine from that at which the guide a^3 is located the machine-frame is left open, so 70 that the blank strips from which the box-sections are made may be readily introduced endwise into the horizontal guide-channel z , just in front of the saws b .

Mounted to reciprocate with a long slow 80 stroke within the horizontal guide-channel z forward of the saws b and interlined therewith is a transversely-extended feed-head c , which is of such length that it will pass between the saws b , as hereinafter described. 85 As shown, the feed-head c has depending racks c' , with which spur-gears c^2 on a transverse shaft c^3 are in mesh. Said shaft c^3 is mounted in suitable bearings in the side brackets a' , and it is provided at one end with 90 a pinion c^4 , which is engaged and operated as hereinafter described.

Just to the rear of the saws b are several spring-catches, which serve to prevent the return movement of the sections cut off by 95 the saws b . As shown, two of these spring-catches are secured in a removable spring-held section a^5 of the bed-plate a , and one of the said catches is secured in each of the overhead guides a^4 . As shown, each of these 100 spring-catches comprises a plunger d and a removable socket or holder d' , in which said plungers are spring-mounted. Said plungers d have cam ends, which cause them to recede

when the box-sections are forced against them by the reciprocating head c .

Mounted in suitable bearings and extending parallel to each other just rearward of the catches d d' is a pair of transverse counter-shafts or tool-mandrels f , which are provided with cutting-tools f' and pulleys f'' , over the latter of which a power-driven belt (not shown) would be run. The cutting-tools f are of the proper form to cut the "bee-entrance screws" in the edges of the box-sections, the lower members being mounted to work through openings f^3 in the bed-plate a , while the upper members are mounted to work through openings f^4 , formed in each of the overhead guides a^4 .

Rearward of the cutting-tools f and located one at each side of the machine, being mounted within suitable bearing-brackets g on the side brackets a' , is a pair of vertical shafts or saw-mandrels g' , which are provided with pulleys g^2 , over which power-driven belts (not shown) are run to impart motion to the said shafts. At their upper ends the said shafts or mandrels g' are provided with vertically-spaced saws g^3 , that project through the sides of the guide-channel z far enough to engage the ends of the box-sections which are fed past them, and thereby to form in the ends of the said sections the tongue-and-groove connections.

At its delivery end the horizontal guide-channel z is curved and then extended vertically downward, this continuation, as shown, being formed by a pair of parallel channel-strips k , turned with their flanges inward, so as to embrace the ends of the partially-completed box-sections and to thereby guide the same for flatwise movement downward onto a shelf or table a^6 , which is supported between the rear ends of the side brackets a' . The lower ends of the guide channels or strips k are rigidly secured to the table or shelf a^6 , and a narrow slit or opening k' is formed in the flanges of said guides k just above the table a^6 , these slits being just wide enough to permit the cut box-sections to be ejected one at a time. The box-sections are ejected one at a time by the action of a plunger or ejector m , which is mounted in suitable guides on said shelf a^6 and is provided with a thin lip or blade m' , which works through the said slits k' . The plunger or ejector m is reciprocated from a pitman m^2 , pivoted thereto at one end and provided at its other end with an eccentric-strap m^3 , which works on an eccentric m^4 , carried by a transverse counter-shaft m^5 , suitably mounted in the side brackets a' . This shaft m^5 is provided with a pulley m^6 (shown only in Fig. 3) over which a power-driven belt (not shown) runs to impart motion to said shaft and the parts driven thereby.

At one end the shaft m^5 carries a sprocket m^7 . Standing in line with the sprocket m^7 and suitably journaled at n on one of the frame-brackets a' is a large sprocket n' , which car-

ries a crank n^2 . A sprocket-chain n^3 runs over the sprockets m^7 and n' . The crank n^2 is pivotally connected to one end of a rack-bar n^4 , the teeth of which engage the teeth of the pinion c^4 , heretofore noted as being carried by the counter-shaft c^3 . As shown, the free end of the rack-bar n^4 is supported and guided in proper line for engagement with the pinion c^4 by a keeper-bracket n^5 and an antifriction-roller n^6 .

Mounted in suitable bearings p , which are adjustably mounted on the rear ends of the frame-brackets a' by means of set-screws p' , is a transverse shaft or tool-mandrel p^2 , which carries V-shaped cutters p^3 . The V-shaped cutters p^3 are adapted to cut the corner-grooves at three different points on the box-sections as they are ejected by the ejector or discharge-head $m m'$. This shaft p^2 is provided with a pulley p^4 , over which a power-driven belt (not shown) is run to impart motion to said shaft.

At one side and at the intermediate portion of the downturned extension of the guide-channel z is a retaining-spring t , one end of which is secured to one of the channel-guides k and the other end of which normally projects inward, as best shown in Figs. 3 and 5. Mounted for vertical movement in suitable guides formed in each guide-channel k is a sliding block or carrier t' , which is normally held upward to its limit by the tension of a spring t^2 . Each block t' carries a trip-spring t^3 , which has an extended finger t^4 and an inturned lip t^5 , which lip projects into the guide-channel in position to engage the ends of a box-section which has been dropped onto the same. Normally the parts just noted stand as indicated in Figs. 3, 4, and 5.

Extending transversely of the machine and in line with the fingers t^4 of the trip-spring t^3 is a sectioned plunger t^6 , mounted in suitable bearings t^7 on a transverse bar t^8 , which is secured to the guide-channels k . Springs t^9 normally force the plunger-sections t^6 inward or together. The said plunger-sections t^6 are forced outward or separated by a wedge t^{10} , guided by a keeper t^{11} and moved by a cam-lever t^{12} , which is suitably pivoted or supported at t^{13} and is subject to the action of a cam t^{14} , carried by a shaft t^{15} , which shaft t^{15} is driven by and movable with the sprocket n' and crank n^2 , heretofore noted. The relative position of the cam t^{14} and its timed action on the cam-lever t^{12} will appear in the description of the operation. As shown, a pair of leaf-springs t^{16} project from a transverse bar t^{17} , which connects the lower rear portions of the guide-channels k . These springs t^{16} serve to hold the box-sections flat against the table a^6 while they are being ejected and acted upon by the corner-groove-forming cutters p^3 .

The operation of the machine above described, briefly summarized, will be substantially as follows: The blank strips from which the sections are to be formed are collected by

the operator and placed side by side, the number varying at different times. No exact number is necessary as long as the capacity of the machine, which would usually be 5 twenty or twenty-five at a given feed movement of the feed-head *c*, is not exceeded. Ordinarily a small number would, of course, be gathered and fed at one time to the machine. The strips collected and placed side 10 by side are moved endwise and transversely of the machine just in front of the saws *b* and just to the rear of the feed-head *c*, their inward movements being limited by the guide-surface *a*². Each rotation of the sprocket *n*¹ and crank *n*² gives the feed-head *c* one complete feed-stroke and return movement, and each feed movement of the said feed-head will carry all of the strips fed thereby to the 15 rear of the saws *b*, so that the box-sections are thereby cut to the proper length and deposited between the parallel end guides *a*². As other box-sections are cut off and fed into the guide-channel *z* the sections previously cut will be forced onward a distance corresponding 20 to the total thickness of the sections fed in by the last feed movement of the head *c*. As the box-sections are fed sidewise past the cutters *f* the bee-entrance grooves will be formed, and as they are forced still 25 farther onward the saws *g*³ will cut the interlocking tongue-and-groove joints in the ends of the said box-sections. The sections after 30 passing the saws *g*³ are fed through the curved portion of the extension of the channel *z*, and 35 in passing this curved portion they are fed sidewise, but are turned from vertical to horizontally-disposed positions. Said box-sections being fed in close engagement through the said curved section are prevented from 40 becoming mixed or losing their proper relation to each other, and this result is further insured by the retaining-spring *t*, (see Figs. 3 and 5,) which spring engages the adjacent ends of said sections and forces the opposite 45 ends thereof against the opposite guide-chamber *k*, thereby frictionally holding the stack of sections wherever set or left by the previous feed movement of the feed-head *c* acting 50 through the intermediate box-sections in the channel *z*. If after passing the spring *t* the box-sections were permitted to drop one by one, they would in falling turn edgewise and not be properly delivered to the bottom of the guide-channel. To obviate this action, 55 the device previously indicated, and the operation of which will now be described, has been provided. When the feed-head *c* moves toward the saws *b* in the feeding action, the box-section which stands immediately above 60 the inturned lips *t*⁵ of the trip-springs *t*³ will engage the said lips and force the blocks *t*⁶ downward against the tension of the springs *t*³. As the said feed-head *c* closely approaches the limit of its extreme movement the cam *t*¹⁴ on the shaft *t*¹⁵ will strike the cam-lever *t*¹² and force the wedge *t*¹⁰ between the inner 65 ends of the plunger-sections *t*⁶, thereby forc-

ing said plunger-sections outward against the tension of their springs *t*³. As the finger portions *t*⁶ of the trip-springs *t*³ are of sufficient vertical extent to always stand in line with the outer ends of the plunger-sections *t*⁶ the outward movements of said plunger-sections will engage the same and force said trip-springs *t*³ outward far enough to carry their lips *t*⁵ from under the engaged box-section. This being done, all of those box-sections which were forced below the tension-spring *t* will drop together to the bottom of the guide-channel, while the box-sections engaged by the said tension-spring *t* will be held in position until forced below the same by the next feed movement of the feed-head *c*. The sliding blocks *t*⁶ and parts carried thereby being released, as above described, will be immediately thrown upward to their normal positions by their springs *t*³.

As clearly shown in Fig. 2, the sprocket *m*⁷ on the shaft *m*⁵ is much smaller than the sprocket *n*¹. In practice the difference in the size of the said sprockets would usually be much greater than in the illustration given in the drawings. Hence it of course follows that the ejector or discharge-head *m* *m*¹ will be reciprocated several times while the feed-head *c* is being reciprocated once. Each reciprocation of the ejector or discharge-head ejects edgewise one of the box-sections, and as this ejector may be run at a very high rate of speed and, further, as the speed of the ejector is the only limitation on the speed of the machine it of course follows that a machine of high efficiency or of great speed capacity is made possible. As the operator can collect a quantity of blank strips to be fed to the machine by one operation, it is not of course necessary for him to supply strips to the machine at each reciprocation of the feed-head *c*. He is therefore given more time to collect and properly select the blanks, and with less effort by the operator the machine will turn out a great deal larger amount of work than would be possible with any machine constructed to feed but a single blank or strip at each feed movement.

The machine above described is of course capable of many modifications within the scope of my invention.

What I claim, and desire to secure by Letters Patent of the United States, is as follows:

1. The combination with a guide-channel through which the box-sections are fed flatwise, of a feed device driven relatively slow and adapted to feed a plurality of sections flatwise into said channel, at each feed movement, box-section-forming mechanism acting on said sections as they are passed through said channel, an ejector driven relatively fast and arranged to eject the box-sections edgewise, one at a time, and cutters acting upon said sections as they are ejected, substantially as described.

2. The combination with a horizontally-extended guide-channel having a downturned

delivery-section, of a feed-head reciprocator longitudinally of and at the receiving end of said channel, an ejector reciprocating transversely of and at the lower end of said down-
5 turned channel-section, which channel passes said box-sections flatwise, and which feed device is adapted to deliver a plurality of said sections flatwise to said channel, and section-forming cutters operating upon said box-sections while they are subject to the said feed device and ejector, substantially as described.

3. The combination with a horizontally-extended guide-channel having a downturned delivery-section, of a feeding device operating to feed the box-sections flatwise into and through said guide-channel, section-forming cutters operating on the box-sections as they are passed through said channel, a spring-pressed section holder or carrier acting upon
15 the sections in the downturned portion of said channel, and a trip for releasing said section-holder, substantially as described.

4. In a machine of the character described, the combination with an upright guide channel or section through which the box-sections are fed flatwise, of a box-section carrier or support yieldingly held upward but adapted
20
25

to be depressed, and an automatic trip for releasing the same to permit the return movement thereof after having been depressed, 30 substantially as described.

5. The combination with a horizontally-extended guide-channel having a downturned delivery end, of a relatively-slow feed device delivering box-sections flatwise into said guide-channel, a relatively-fast ejecting device working transversely of the downturned delivery end of said guide-channel for discharging the sections edgewise, cutters operating on the sections as they are passed through said guide-channel, a friction device engaging the slats in the downturned portion of said guide-channel, a section-carrier below said friction device yieldingly held upward, and an automatic trip for releasing said carrier from said sections, while depressed, 35 40 45 substantially as described.

In testimony whereof I affix my signature in presence of two witnesses.

CHARLES MONDENG.
